UNITED STATES PATENT OFFICE.

CHARLES H. SCHURR, OF CLEVELAND, OHIO, ASSIGNOR TO THE LEES-BRADNER COMPANY, OF CLEVELAND, OHIO, A CORPORATION OF OHIO.

GEAR-GRINDING MACHINE.

Application filed August 14, 1925. Serial No. 50,239.

This invention relates to an apparatus for grinding or cutting teeth or tooth faces of gears, for example, gears having teeth generated according to the involute system.

5 An object of my invention is to provide a machine of the type mentioned wherein formed gears may be very accurately finished by grinding.

Another object of my invention is to provide for the successive grinding of a plurality 10 of formed gear teeth in a very efficient manner.

Another object of my invention is to provide a machine of the above character which 15 may be stopped automatically at any predetermined point of the grinding operation.

Another object of my invention is to provide improved tool dressing means for a grinding machine of the above character 20 whereby the grinding tool may be automatically dressed at intervals during the grinding operation.

Another object of my invention is to provide a machine of the type mentioned wherein 25 certain mechanism is employed to impart a "rolling" motion to the work as the work carriage is reciprocated.

Other objects and advantages will become 30 apparent as the description of an embodiment of my invention progresses, reference being made to the accompanying drawings forming a part of the specification and in which like characters are employed to designate like parts throughout the same.

35 In the drawings—

Fig. 1 is a front elevation of my improved gear grinding machine, showing the tool dressing mechanism and means for operating the same;

40 Fig. 2 is a rear elevation of my invention showing the gear indexing mechanism partly in section;

Fig. 3 is an enlarged front elevation of a portion of my machine, partly in section and 45 taken on line 3—3 of Fig. 4 illustrating the means for moving the work carriage;

Fig. 4 is an enlarged horizontal section taken on line 4—4 of Fig. 1 and Fig. 7;

Fig. 5 is a fragmentary section taken on line 50 5—5 of Fig. 3 and Fig. 4;

Fig. 6 is a section taken on line 6—6 of Fig. 5;

Fig. 7 is an enlarged elevation of the clutch 55 12; timing mechanism; see also Figs. 4, 10, 11 and

Fig. 8 is a section on line 8—8 of Fig. 7, but showing the parts shifted in different position than shown in Fig. 4;

Fig. 9 is an enlarged vertical section on line 9—9 of Fig. 2;

Fig. 10 is a section on line 10—10 of Figs. 1 and 7 but to larger scale than Fig. 1 and smaller scale than Fig. 7;

Fig. 11 is section on line 11—11 of Figs. 1 and 4;

Fig. 12 is a section on line 12—12 of Figs. 1, 4 and 7;

Fig. 13 is an enlarged section on line 13—13 of Fig. 1;

Fig. 14 is an enlarged axial section through 70 the tool and shaft assembly;

Fig. 15 is an enlarged section on line 15—15 of Fig. 1;

Fig. 16 is an enlarged section on line 16—16 of Figs. 1 and 14; and

Fig. 17 is a vertical section of certain elements taken on line 17—17 of Figs. 4 and 8.

In the drawings, I provide a base 1 which includes a main supporting frame 2 and a housing 3. This housing encloses the drive 80 for the carriage shifting mechanism, control clutches and other mechanism which will be described more fully as the present description progresses.

Power for driving the apparatus may be 85 derived from power shafting such as is usually found in machine shops or may be applied directly by connecting a motor, or the like, to the drive shaft of the apparatus. I prefer to take power from a driven pulley by 90 means of a belt (not shown) which drives pulley 4, shaft 5 and pulley 6 on one end of the shaft, and pulley 7 on the other end of the shaft 5. An idler pulley 6' may be provided to take the power belt if so desired.

A belt 8, or the like, connects the driven pulley 7 with a pulley 9 keyed to shaft 10 whereupon power is applied to revolve shaft 10 and the pinion 11 which is keyed to shaft 12 through a suitable clutch mechanism. A 100 clutch collar 13 having teeth 14 is slidably keyed to shaft 10 and when moved to engagement with the pinion 11 having similar clutch teeth 14, will transmit power to rotate shaft 12. The collar is actuated by a crank 15 which is keyed to turn a shaft 16 and to rock a forked member 17 (see Fig. 12) which is provided with blocks 18 pivotally mounted therein to slide the collar 13 along shaft 10. By turning the crank in a clockwise direction 110

the clutch is disengaged and power is cut off from the machine beyond this point. Shafts 10 and 12 are in alignment and their adjacent ends telescope as at 19.

5 The shaft 12 is mounted in suitable bearings consisting at one end of a clutch sleeve member 25 rotatably carried in a bearing support 26 formed within the housing, and at the other end an axial bearing seat 27 formed in 10 the end of shaft 28. Shaft 28 is rotatably supported by the housing at one end and a bearing support 29 at the other end.

15 A suitable power clutch mechanism including a sleeve 30 slidably keyed to the shaft 12 simultaneously applies power to a wheel dressing mechanism at predetermined intervals and relieves the power connection to the work carriage as will be described. Thus while the wheel or tool 31 is being dressed the 20 work carriage may be locked stationary with the work out of engagement with the wheel for a predetermined number of dressing operations. The sleeve 30 is slidable on the shaft

25 12 and rotates with it, and is provided with an annular rim 32 which engages a notch 34 formed in the sliding bar 33. This bar is 30 slidable within aligned openings or bearings formed in the supports 26 and 29 and is provided with notches 35 and 36. Clutch plates

35 30 or notch engaging surfaces 37 and 38 are formed integrally on shaft 28 and sleeve 25, respectively, and are each provided with radial openings (not shown), the edges of which are adapted to engage one of the adjacent edges of the notches 35 or 36, respectively, according to the position of the sleeve 30. From description to follow later herein, it will be seen, that when the bar 33 is in the position shown in Fig. 4, the periphery of

40 the plate 38 will register with the notch 36 and will be free to rotate therein, thus rotating the sleeve 25 and the gear 20 to operate the dressing mechanism and disengaging the power connection to shaft 28, but when the

45 sleeve 30 is in its other extreme position, that is, to the left in Fig. 4, the bar 33 will have been moved so that the notch 35 will register with the periphery of plate 37 while the notch 36 will have assumed a position out of alignment with the plate 38 whereby the radial edge of said plate will engage the edge of the notch 36. In this position power will be dis-

50 engaged from the dressing mechanism and will be transmitted from shaft 12 through the clutch mechanism to rotate the shaft 28. The sleeve 30 is provided with plate engaging

55 clutch surfaces at 39 and 40 which engage the faces of the plates 37 and 38, respectively, when the sleeve is moved to one of the positions just described. A radially projecting finger 41 having beveled walls is formed on the sleeve 30, which engage with similar beveled surfaces formed in the clutch operating bars 42 and 43. These bars are slidably 60 mounted within the casing 3 and are similar

to each other except that the forward contacting surfaces thereof are oppositely beveled. Each of the bars is provided with a centrally and oppositely disposed rack section 44 with which a pinion 45 is in mesh so that rotation of the pinion will slide the bars in opposite directions. As shown in Fig. 17, the pinion 45 is formed on one end of a shaft and a similar pinion 47 is formed on the other end. A second set of slideable bars 48 and 49 disposed on opposite sides of the pinion 47 and having teeth thereon in mesh with the pinion, is provided as shown in Fig. 8, and are disposed preferably above the bars 42 and 43. The bars 48 and 49 are provided on their outer ends with contact members which are adjustable within the bars 48 and 49 respectively and have preferably conically shaped heads 50 and 50', respectively. Adjusting nuts 51 threaded upon the contact members serve to hold the contact members in adjusted position.

55 Referring now more particularly to Fig. 4, a gear 52 is keyed to rotate with shaft 28 and meshes with an idler pinion 53 carried by the casing. A gear 54 is keyed to a shaft 55 which rotates upon suitable ball or roller bearings 56. The said gear 54 is removably mounted on one end of the shaft being held by a nut 54' as shown while to the other end of the shaft is secured a member 57 having a cam groove 58 formed therein about its periphery. Referring to Fig. 3, where I have shown the path of the groove partly by dotted lines, I provide a connecting rod 59 having a groove-engaging roller 60 adjustably mounted on one end to seat within the groove and to follow its path during revolution of the member 57, imparting reciprocatory motion to the pitman and the work carriage 61 to which the other end of the pitman is adjustably secured at 62. The roller mounting 63 slides along a guide rail or the like 63' formed on the casing to provide for rigidity of operation with a maximum of efficiency.

60 Referring to Fig. 4 again, it will be noted that the member 57 is keyed to the shaft 64 which is a reduced extension of shaft 55 and is locked thereon against axial movement by a nut 65. The gear 54 is provided on its inner face with a roller engaging trip 66, shown in detail in Figs. 5 and 6. This trip extends almost to the outside diameter of the teeth on the gear and is so positioned on the gear that it engages a roller 67 carried by one arm of a bell crank 68 which is mounted to rock on the casing. The other arm of the bell crank is connected to suitable plunger operating and associated mechanism by means of a connecting rod 69. This mechanism will be described in detail as the present description of my invention progresses.

65 A second trip device 70 consisting more essentially of a cam surface is formed on the outer face of the gear 54 and is timed to

engage and slide the bar 71 outwardly or to the right in Figs. 2 and 6 and to the left in Fig. 4 just after the roller 67 has engaged the outer peripheral surface of the trip 66.

5 Suitable mechanism for determining the periods over which the clutch generally designated at 30, is operated to alternately connect the source of power to the tool dressing mechanism and to mechanism for reciprocating the carriage and operating other mechanism associated therewith, is provided in the forward portion of the casing and is shown partly in detail in Figs. 7 and 12. This mechanism includes a cam 72 which is adjustably secured to a shaft 73 by a nut 73' through cone members 73' and is driven by gear 11 and pinion 11' keyed to shaft 73, Fig. 12.

An arm 74 having a hub 75 is pivotally mounted to rock about a shaft 93, Fig. 7, and is provided with a roller 76 on its outer end which engages the periphery of the cam surface 72' of the cam 72 and rides thereover. About midway of the arm is pivoted a dog 77 normally under tension of a spring 78 to cause the dog to engage the teeth 79 of a ratchet or disc 80. The ratchet 80 is keyed to a sleeve 100, Fig. 10, and is rotatable about an axis coincident with the pivot axis of the arm 74 and independently therefrom. A spring 81, Fig. 7, is secured on one end to the arm 74 and at the other end to the casing 3 to normally maintain the arm roller in contact with the periphery of the cam 72. For each rotation of the cam 72 the dog 77 will advance the ratchet in a counter-clockwise direction the distance of one tooth. A trip plate 82 having pointed projections or tripping members 83 and 84, Fig. 8, thereon is secured to rotate with the ratchet 80, the tripping members being positioned on the plate to engage the contact members 50 and 50', respectively. The contact members are offset so that the tripping members will strike only their respective contact during rotation of the ratchet 80. A second trip device 85 is secured to rotate with the ratchet and has an inclined arm engaging surface 86 which is adapted to engage the arm 87 pivoted to the casing at 88. Rocking of the arm to the right, as in Fig. 7, will operate the power clutch collar 13 through the connecting rod 89, crank 90 and shaft 16, to sever the power connection from the machine beyond the clutch 13.

55 A sleeve 91 carrying a trip bearing member 92 is mounted to be rotated coaxially with but independently of the ratchet 80 when desired and its outer peripheral end carries trips 94 and 95. This sleeve being keyed to the shaft 93 is free to be set at any desired point about its axis of rotation and this is accomplished by providing a dial 96 keyed to the other end of the shaft 93 and having clutch teeth 93' adapted to cooperate with similar clutch teeth formed on a collar 99. A

ring 97 may have markings thereon and is provided with a seat 97' on its inner side face which receives a spring pressed ball 98 mounted in the frame 3 when the ring is rotated to zero position to normally hold and indicate that the ring is in its zero setting position. A set screw 99' is provided to lock the ring to the collar 99. The collar 99 is intermediate the ring 97 and the dial 96 and may have indicating markings thereon. This collar is keyed to sleeve 100 to rotate therewith and is provided with an annular groove to seat a spring 101. The spring normally is under compression between the members 96 and 99 and serves to separate said members when the nut 100' is unscrewed. By the use of the mechanism just described and shown in enlarged detail in Fig. 10, the operator of the machine is enabled to select a setting of the dial 96 whereby the member 92 is rotated so that its trips 95 and 94 are spaced from the trips 83 and 84, respectively, of the ratchet 80. The distance between the trips thus selected is equal to a given number of teeth of the ratchet and corresponds to the number of teeth to be ground on the blank. A more detailed description of the operation of the selecting mechanism will be given when the operation of the entire machine is described.

55 Suitable mechanism for imparting a rolling movement to the gear blank as the carriage, on which it is mounted, is reciprocated, is provided and operates in conjunction with a mechanism for indexing the blank. The indexing mechanism includes a bar 71 previously described as being reciprocated by having its one end engaged by the trip 70 in the casing. A rod 103 slidable within suitable bearings 104 in a casing 105 is provided with a substantially central depressed rack portion 106 therein which is engaged by the teeth of a pinion 107 on a shaft 108. The one end of the rod 103 abuts the free end of the bar 71 as shown in Fig. 2. A retracting spring 109 is secured to the rod 103 and adjustably fastened to the casing 105 and normally pulls the rod to the left. The pinion 107 is mounted in suitable bearings and keyed to its shaft to rotate therewith is a larger pinion 110 which meshes with a freely rotatable gear 111. This gear 111 is provided with an annular flange on one side and keyed thereto is a ring 112 having a dog 113 pivotally mounted thereon for engagement with an adjustable shield 114 over which it rides when out of engagement with a ratchet 115. The dog 113 is loosely pivoted to the ring 112 and during movement of the gear 111 rides over the edge of the shield and engages the teeth of the indexing ratchet 115 which is keyed to the main spindle 116. Engagement of the dog with the ratchet 115 and further movement of the ring 112 will therefore cause the spindle 116 to be 120 125 130

rotated. As the ring 112 is rotated in the opposite direction, the dog is made to disengage the ratchet 115 and again ride over the shield. The shield is shiftable about the ratchet 115 so that its position determines the number of teeth on ratchet 115 which are to be engaged by the dog thereby shifting the gear blank on the end of the spindle the distance corresponding to the number of teeth engaged by the dog. Suitable securing means at 117 maintain the ratchet 115 locked on the spindle.

It will be noted that I have provided a bearing 118 between the frame 119 and the gear 111 so that free movement of the gear 111 upon the spindle and frame is permitted. By providing a bar 71 which is removable from the casing 3, I may very readily disengage the automatic means for operating the indexing mechanism by simply removing said bar. The blank may then be indexed by hand if desired.

The main spindle 116 is provided with a central opening running longitudinally thereof, but of different bores at the ends thereof. The walls of the opening are tapered slightly at each end as shown in Fig. 9. A spindle 120 being tapered to snugly fit the walls of the opening at the rear end, as shown in the figure, is provided with a removable gear 121 keyed to its free end, a nut or other fastening means 121' being employed to prevent accidental displacement of the gear and to provide for interchanging gears of different sizes according to the size of the blank to be ground. A spindle 122 having tapered walls to snugly seat within the tapered opening at the other end of the main spindle extends outwardly therefrom, its outer end being provided with converging walls and terminating in a blank holding end 123. A blank 124 is shown secured on the end of the spindle by a nut or the like 125. A rod 126 is threaded at one end within the spindle 122 and passes axially through the spindle 120. Its free end is provided with a shouldered portion 127 having an inner cone surface for seating within the end of spindle 120. By applying a wrench to the shouldered end and turning the spindles are drawn together and locked within the main spindle 116 by virtue of the tapered walls. The main spindle 116 is rotatably mounted within the carriage 61 and has a collar 128 secured thereto and abutting a bearing sleeve 129 keyed to the spindle 116. A suitable bearing consisting of plates 130 and spaced balls or rollers 131 engages the other end of the sleeve and a spring 132. This spring normally exerts a pressure against the outer bearing plate and maintains the spindle seated within the casing in the proper position and prevents outward axial movement thereof. A shield 133 is provided to rotate with the spindle to prevent the entrance of bits of metal ground from the blank into the

interior of the spindle and damaging the bearing surfaces.

Suitable means for rolling the blank and spindle, engage gear 121 on the rear end of the spindle 120, and consist of two rack bars 134 and 135 arranged in parallel relation with the teeth of one bar slightly offsetting the teeth of the other bar. Upon reciprocating the carriage 61, the gear 121 will roll along the racks and will impart such rolling motion to the blank through the spindle. As has been described, the rack bars are so placed that their teeth are slightly offset with respect to each other and when they are brought into engagement with the gear 121, the slightly offset teeth will readjust themselves to insure a perfect meshing with the teeth of the gear 121. The bar 135 is preferably rigidly secured to the plunger 136 while the bar 134 is slidably mounted therein. The bar 134 is normally forced to the left in Fig. 2 by an adjustable spring held within a casing 136'. Thus when the gear 121 is out of engagement with the rack bars, the spring will cause bar 134 to move to the left and will cause the teeth of the respective bars to be slightly offset with respect to each other. When the gear 121 is in engagement with the bars, bar 134 will provide a means for preventing back lash in the gear 121.

The plunger 136 reciprocates vertically within a casing 137 and its lower end is provided with a plate 138 and a nut 139 for securing the plate to the plunger. A bushing having a flanged edge 140 is mounted in the casing 141 while the plate 138 seats against the flange 140 as shown in Fig. 9. A cover plate 141' is secured by bolts or the like to the casing 137. The casing 141 is provided with extended guiding edges 142 at its lower end. The upper end of the casing likewise carries a bushing 143 which is in alignment with the bushing 140 and the plunger is movable therein.

Suitable means of adjusting the limits of the plunger movement when larger or smaller blanks are to be ground, has been shown in the form of providing means for adjusting the plunger casing 141 consisting of adjusting screws 161. By loosening the screws and breaking the connection through the cone clutch members 152 and 154 by loosening the nut 155, the casing 141 may be shifted vertically up or down as desired until the correct adjustment is reached for the particular size gear being ground. Vertical movement of the casing 141 is accomplished by inserting a bar or the like in holes formed radially in the member 154 and applying force to the bar to rotate the member 154 which will cause the gear 145 to rotate to raise or lower the plunger. Then the screws 161 and nut 155 are tightened to maintain the casing in the desired adjusted position and to re-establish the connection through the cone clutch.

Teeth 144 are formed on the rear face of the plunger for a portion of its length and engage the teeth formed on the gear 145. The connecting rod 69, which is pivotally connected at one end to the member 68 and is reciprocated thereby, is connected at its lower end to a gear 146 rotatably mounted on a shaft 147. The gear 146 is provided with teeth partially around its periphery and meshes with a gear 148. A toothed clutch 150 having one member carried by the gear 148 is provided, and transmits power from the gear through a shaft 151 having a reduced end 153 and a male cone clutch member 152 on its opposite end. The reduced shaft end 153 is disposed axially within a sleeve 153'. A female cone clutch member 154 which cooperates with the male clutch member 152 is carried on the outer end of the sleeve, and a nut 155 is provided for locking the sleeve and shaft against relative movement. A gear 145 is keyed to the other end of sleeve 153' and meshes with the rack teeth 144 to raise and lower the plunger and thereby engage and disengage respectively the bars 134 and 135 with the gear 121. An arm 157 is rockable with the gear 148 and a spring 158 for normally maintaining the rack 134-135 in engagement with the gear 121 when the plunger tripping mechanism is inoperative. It is attached at one end to the arm and at its other end to a pin or the like 159 carried by the main frame. When the trip is actuated, the plunger is moved downwardly and the spring 158 is placed under tension, and when the roller 67 leaves the trip 66 the rod 69 is moved downwardly, power will be transmitted through gears 146 and 148 and through the cone clutch 152 and 154 to the gear 145 and plunger 136, moving the latter upwardly and bringing the bars 134-135 into the path of movement of the gear 121.

Referring now to Figs. 1, 4, 11, 13 and 15, I will describe the mechanism for performing the dressing operations.

In Fig. 4 I have shown how the power is taken from the main driving parts within the casing. As the shaft 22 mounted in sleeve 23 and the helical gear 21 rotate, bevel gears 24 and shaft 170 are also caused to rotate and transmit power through the universal coupling 171 and shaft 172 and through helical gears 173 and 174 to a shaft 175 mounted in suitable bearings 176 in a casing 177 (Fig. 13).

A cam plate 178 is secured to rotate with shaft 175, by a nut 179 and is provided with a T-slot running around one face as shown in Fig. 15 at 180. Cam members 181 and 182 are adjustably carried by the plate 178 and are secured thereto by means of nuts 184 and headed fasteners which are carried within the slot 180. It is apparent therefore that these cam pieces may be adjusted in spaced or contacting relation upon the plate. Al-

though I have shown but two cam members on the plate I may use a greater number since each cam surface positively operates the dressing tool and by using a given number of cams I am able to dress the wheel a given 70 number of times during the dressing operation. I may use only one cam and thereby limit the dressing operation to but one contact between the tool and the wheel. As shown in Fig. 1, I have provided cam members 181 and 182, the former having cam surfaces at such an angle to the base of the cam that it will cause the tool to move quickly over the working edge of the tool 31 while the latter cam will be provided with cam surfaces 80 of more gradual rise and fall so that when this cam comes into operative position for moving the tool to dress the wheel the movement of the tool will be slower than the former movement. The result obtained is that the first 85 cam provides for a quick or rough dressing of the wheel while the latter cam provides for a more gradual or finish dressing of the wheel. As pointed out above I may use additional cams, if desired, and these may have 90 surfaces of the same or of varied inclinations. It is also to be understood that I may space the cams to any desired position on the plate to provide for an interval between the rough and finish dressing operations. Keyed to a 95 dressing tool operating shaft 185 is an arm 186 having a cam engaging roller 187 mounted on its free end. The shaft 185 is rockable in suitable bearing and keyed to it is an arm 188 carrying at its outer end a link 192, connecting to the bell crank 191. An adjustment device for regulating the swing of the tool, when the shaft 185 is rocked is carried by an arm 193 which is keyed to the shaft 185'. This adjustment device consists of a thumb 100 screw 189 having a central longitudinal threaded opening. A threaded member 190 is adjustable within the opening and is swivelly secured to one arm of a crank 191 which is rotatably mounted on the dressing 110 tool carrying shaft 185'. A spring 195 is attached at one end to the arm 188 and to the casing 196 at the other end for normally maintaining the roller 187 in position to contact with the cams on the plate 115 178 as they are rotated into contacting position. A trip 197 is secured to the plate 178 in a manner similar to the cams 181 and 182 and is so positioned on the plate that it contacts with a trip rod 198 to operate suitable 120 tool advancing mechanism. The rod 198 is provided on its trip engaging end with a suitable engaging nose 198' for the trip 197. The other end of the rod is connected through a swivel 199 and a link 200 to a plate 201 which 125 is loosely mounted on the hub of a ratchet 202 which is keyed to the shaft 203' and carries a pawl 203 engaging ratchet 202 keyed to the shaft 203'. A hand wheel 204 is also keyed to the shaft 203' for manually adjusting the 130

wheel spindle. A collar forming a shield plate 208 is adjustably carried on a bushing 208' and may be secured in various positions about the ratchet 202 to limit the number of 5 teeth engaged by the pawl 203 during its movement and consequently regulating the advance of the tool. It will be seen, therefore, that I have provided for both manual and automatic operation of the tool advancing mechanism. A worm 205 is also keyed 10 to shaft 203' at the other end thereof, being secured thereto by a nut 205', and meshes with a worm gear 206.

Referring now more particularly to Fig. 14, I have shown the worm 205 and the worm gear 206, the latter being internally threaded as at 207. A suitable casing 196 forms bearing surfaces for the worm gear and also is extended toward the rear as at 209 to provide 15 a housing for the drive pulley 210 which is rotatably mounted in suitable bearings 211 and is keyed to the reduced end of the tool spindle 212. Connection to the power source for rotating the tool is made by means of a 20 belt or the like 210' running over the pulley 210 through an opening in the frame of the machine and over suitable belt tightening idlers to the drive pulley 6. Keyed to the 25 spindle 212 is a sleeve 213 having a shoulder 214 formed on one end and secured against longitudinal movement to the right in Fig. 14 by a nut 215. The sleeve 213 is held toward the right in Fig. 14 by a compression spring 216 one end of which abuts against the shoulder 214 on the sleeve. The other end of the 30 spring 216 abuts upon one face of an annular ball bearing 217, the other face of which abuts, as shown in Fig. 14, upon an internal shoulder of the sleeve 218. By this means, 35 since the spindle 212 is keyed to the sleeve 213, the spindle is resiliently held axially toward the right in Fig. 14 and its position determined by a flange 217' on the spindle thrusting upon a washer 218', and the latter thrusting upon the end of the sleeve 218. Since the greater part of the length of the 40 spindle 212 extends to the right of the washer 218', and since the working planular face 241 of the grinding wheel 31 which is mounted 45 on the spindle 212, as will be described, lies approximately in the plane of the washer 218', the lengthwise contraction and expansion of the spindle 212 due to change of temperature 50 will not materially move the position of the tool 31 and will permit its working face 241 to be accurately maintained in a predetermined 55 position. The sleeve 218 is movable longitudinally within the casing 196 by means of the internally threaded worm gear 206 and 60 threads 221 on the sleeve, and is provided with a longitudinal slot 219 which registers with the set screw 220 which prevents circumferential movement but allows longitudinal 65 movement of the sleeve 218. The movement of the sleeve longitudinally is very slight

since such movement depends upon the rotation of worm gear 206 whose internal threads are in mesh with the threads 221 on the end of the sleeve 218. A tapered bushing 222 is interposed between the sleeves 213 70 and 218. A plate 223 is bolted to the end of sleeve 218. This plate has an opening through which the spindle is free to rotate and is also provided with an annular flange 224 for engaging the enlarged end of the 75 bushing 222 and preventing its movement to the right in Fig. 14.

At the free end of the spindle I have provided a grinding wheel supporting member 225 having a tapered hub keyed to the tapered end of the shaft 212 and having an annular seat formed therein for the reception 80 of a grinding tool or wheel 31.

A clamping member 226 is adapted to fit over the outer end of the member 225 for 85 clamping the wheel 31 on the supporting member 225. A nut 228 threaded on the member 225 and engaging the member 226 securely holds the two members and tool 31 in clamped position. A nut 229 is provided on the end 90 of the spindle to permit removal of the clamping member 225.

Referring now to Fig. 1, it will be seen that I have mounted the grinding wheel assembly and dressing mechanism on a plate 230. This plate is carried on a frame 231 and is capable of a substantially vertical adjustment with respect thereto. Bolts 232 are provided to lock the plate in the desired adjustment on the frame. The frame 231 is capable of an 100 angular adjustment with respect to the main frame 2 by virtue of the elongated slots 233 and securing bolts 234. An adjusting screw 235 is threaded into the support 236 and passed into a suitable opening in the plate 105 230. A gear 237 keyed to the screw 235 is engaged by a gear 238 keyed to a shaft having a squared end 239. A crank (not shown) may be placed upon the squared end of the 110 shaft for turning the same for making vertical adjustments of the tool 31.

It will be noted that I have provided an opening in the wheel casing 194. This opening has one of its edges 240 in the working plane of the tool 31, that is, in the same plane 115 as the planular face 241 of the tool. It is the purpose of this edge to serve as a guide in setting the diamond dressing tool 242 after inserting a new tool or after the old one has been worn considerably. By placing the cutting edge of the diamond point against the edge 240 of the casing and then tightening the adjusting nuts 243 the tool will be in correct cutting position for dressing the wheel grinding surface. It will also be noted that 120 the dressing tool mounting 244 is adjustably carried in a holder 245 which is keyed to the shaft 185'. Rocking of the shaft by mechanism hereinbefore described will rock the 125 tool holder and diamond point 242 across the 130

working face 241 of the tool 31 for dressing the latter, the dressing periods and quality of dressing being controlled by apparatus hereinbefore described.

5 I will now briefly and more generally describe the operation of the machine with a view to more clearly pointing out how the various operations are performed and co-operate with each other to contribute to the 10 ultimate purposes and objects of the machine in turning out completed work of a high degree of accuracy and quality.

As power is applied to the pulleys 6 and 7, the grinding wheel or other tool 31 is caused 15 to rotate. Power is coupled through the clutch mechanism, shown generally at 13 and manually operable by a crank 15, to a carriage driving and other mechanism within the casing 3.

20 A second clutch mechanism indicated generally at 30 and associated parts is operable to couple the tool dressing mechanism with the drive through clutch 13 or to shift the power directly through from the clutch 13 25 to the carriage reciprocating mechanism, the indexing mechanism and the mechanism for imparting a rolling movement to the blank. As the clutch 30 is shifted from one position to another, it will cause the power to be shifted 30 to either one or the other of its associated mechanisms. The clutch 30, therefore, serves to permit of a dressing operation, while the carriage and other associated mechanism is idle.

35 The mechanism carried within the casing 3 and shown in detail in Figs. 7 and 8 is provided for controlling the movement of the clutch 30. When it is desired to grind a gear blank having, for example, twenty teeth 40 thereon, the clutch may be so timed to connect the power source to the carriage and other associated mechanism until a given number of teeth have been ground and then interposing a period when the dressing mechanism 45 is operative. A second period of grinding and a final period of dressing complete the cycle of operation of the timing mechanism, since at the completion of the last dressing period the source of power is caused to be 50 disconnected from the machine by the shifting of clutch 13 by the trip 85. The timing of the clutch 30 is accomplished by first setting the ring 97 until the seat 97' therein is engaged by the ball 98. This will indicate 55 a zero position or a point from which to count in determining the point at which the dress mechanism is brought into operation. In setting the clutch controlling apparatus the nut 100' is first loosened until the spring 60 101 forces the member 96 outwardly free of the member 99. While in this position, the member 96 is rotated in one direction until its reading indicates that the shaft 93 and arm 92 have been rotated a distance equivalent 65 to twenty teeth, on the ratchet 80. It will

be noted that during this step the ratchet 80 and arm 92 are relatively movable and the trips 94 and 95 have been spaced from trips 83 and 84 respectively, a distance equivalent to twenty teeth on the ratchet 80 since in this 70 particular instance I am describing the grinding of a blank having twenty teeth.

It will be seen that the trips 94 and 95 are fixed relative to each other, as are also the trips 83 and 84. The distance between the 75 trips of the respective sets 94-95 and 83-84 represents the period through which the dressing mechanism is in connection with the source of power through the clutch 30. I find that the trips of each set may be fixed in 80 spaced relation a distance of approximately three ratchet teeth, although any other distance between the trips providing for a greater or shorter dressing period may be utilized, if desired.

85 After the members 96 and 99 have been brought to the proper setting as above described, the nut 100' is screwed in again, locking the members together. When the member 96 is now turned, rotation of shaft 93, 90 arm 92, member 99, sleeve 100 and ratchet 80 is also accomplished. Rotation of member 96 to the right will therefore cause the movement of the trips 94, 95, 83 and 84 now in locked spaced relation to be shifted to the 95 right in Fig. 7. When grinding a blank having twenty teeth the members 96 and 99 are rotated to the right so that the zero point on the ring 97 is now set a distance to the right of a fixed zero mark on the casing 3, equivalent to twenty teeth on the ratchet 80. It will be observed then that the setting is now complete and that upon shifting the clutch 13 so that the source of power is applied to set the machine into operation, the ratchet will be 100 105 rotated step by step to the left in Fig. 7 by virtue of the cam 72 and dog 77 and other associated mechanism.

110 As the rotation of the ratchet and other parts progresses, the trip 94 will engage the contact member 50 and cause the clutch 30 to disengage the carriage shifting and other associated mechanism which has been operating up to this point, and to immediately engage the tool dressing mechanism to cause it 115 to operate. The dressing mechanism operates until the trip 95 engages the contact member 50' when the dressing mechanism will be disconnected from the power source by virtue of the shifting of clutch 30 out of engagement 120 with the dressing mechanism and immediately into re-engagement with the carriage and other mechanism for the second grinding operation. This grinding operation continues until the ratchet has been advanced a distance 125 equivalent to twenty teeth thereon when the trip 83 engages the contact member 50 whereupon the dressing mechanism is again caused to operate while the carriage mechanism is locked in idle position. This second dressing 130

operation continues until the trip 84 engages the contact member 50'.

At the completion of the second dressing operation or when the trip 84 engages the member 50' the trip 85 simultaneously engages the arm 87 and through other suitable mechanism causes the shaft 16 to be rocked and the power clutch 13 to be automatically disengaged from the power source, stopping the machine. It will be noted that the ratchet 80 is advanced to the left in Fig. 7 the distance of one of its teeth for each complete reciprocation of the carriage 61, and that the carriage is only movable when the clutch 30 is engaged with the carriage operating mechanism and disengaged from the dressing mechanism.

The blank may now be removed from the spindle and reversed so that the opposite tooth faces may be ground.

The indexing mechanism, the carriage reciprocating mechanism and the mechanism for imparting a rolling movement to the blank are all operated by mechanism connected to the clutch 30, so that when the clutch 30 is in position to transmit power through to such mechanism, it is disengaged from the dressing mechanism. When so connected, the indexing mechanism is timed through suitable trips to advance the blank carrying spindle when the carriage is to the left in Fig. 2. At this point the plunger 136 is at its lowermost position and the racks 134 and 135 are out of engagement with the gear 121 which is keyed to the rear end of the blank carrying spindle. While the gear 121 is thus disengaged the indexing mechanism is caused to operate to advance the blank by rotating the spindle the desired distance. The shield plate 114 is adjustable over the gear 115 to permit engagement of the spindle rolling dog 113 with only the desired number of teeth on the said gear, thus controlling the advancement of the blank at each complete reciprocation of the carriage.

As the carriage begins to move to the right in Fig. 2 mechanism associated with plunger 136 is caused to move the plunger upwardly so that the racks 134 and 135 are brought into the path of movement with the gear 121. As the carriage continues to move to the right, the gear is caused to roll along the rack and to impart such rolling motion to the blank carried on the other end of the spindle. During such rolling movement of the blank, the blank is caused to move in the working path of the tool 31 and the teeth of the blank are subjected to the action of such tool. Although I prefer to use a grinding tool, I may use any cutting or other tool if desired. The return movement of the carriage will cause the blank to be rolled in the opposite direction and as the carriage approaches the left in Fig. 2, the cycle of operations is repeated.

The number of reciprocations of the carriage and consequently the indexing of the

blank is controlled by the mechanism already described and shown more particularly in Figs. 7, 8 and 10. After a predetermined number of cutting or grinding operations has been completed, the clutch 30 is automatically shifted to connect the power source to the dressing mechanism which causes the tool 31 to be subjected to a rough and a finish dress while the blank is locked in a stationary position by the clutch 30. I may subject the tool to a plurality of rough or finish dressing operations, or both, if desired and may also control the periods through which each of the dressing operations is being conducted.

Immediately preceding each dressing operation the tool advancing mechanism is caused to operate as already described and as shown by mechanism more particularly in Figs. 14, 15 and 16.

It will be noted from the above description of the construction and operation of my machine that I have provided an apparatus which will produce finished gears and the like very efficiently and accurately.

Having thus described my invention I am aware that numerous and extensive changes may be made from the embodiment herein described and claimed, but without departing from the spirit of my invention or the scope of the subjoined claims.

I claim:—

1. In a machine of the class described, the combination of a base, a carriage movable thereon, a spindle rotatably carried by said carriage, a blank carried by said spindle and rotatable therewith, a tool disposed in the path of movement of said blank, indexing means to advance said blank when said carriage has reached a predetermined position on said base, means for imparting a rolling movement to said blank during the movement of said carriage, said last named means including a rack and a gear carried by said spindle and adapted to roll along said rack during the movement of said carriage, and mechanism operable to move said rack into and out of the path of travel of said gear.

2. In a machine of the class described, the combination of a base, a carriage movable thereon, a spindle rotatably carried by said carriage, a blank carried by said spindle and rotatable therewith, a tool disposed in the path of movement of said blank, indexing means for advancing said blank when said carriage has reached a predetermined position on said base, means for imparting a rolling movement to said blank during the movement of said carriage, said last named means including a rack and a gear carried by said spindle and adapted to roll along said rack during the movement of said carriage, and a plunger carrying said rack thereon and operable to move the rack into and out of the path of travel of said gear.

3. In a machine of the class described, the

- combination of a base, a carriage movable thereon, a spindle rotatably carried by said carriage, a blank carried by said spindle and rotatable therewith, a tool disposed in the 5 path of movement of said blank, indexing means to advance said blank when said carriage has reached a predetermined position on said base, and means for imparting a rolling movement to said blank during the movement of said carriage, said last named means including a rack and a gear carried by said spindle and adapted to roll along said rack during the movement of said carriage, and a plunger carrying said rack thereon and operable to move it into and out of the path of travel of said gear, said rack consisting of teeth relatively movable and normally slightly out of alignment when not engaged by said gear.
- 20 4. In a machine of the class described, the combination of a base, a carriage movable thereon, a spindle rotatably carried by said carriage, a blank carried by said spindle and rotatable therewith, a tool disposed in the 25 path of movement of said blank, indexing means to advance said blank when said carriage has reached a predetermined position on said base, and means for imparting a rolling movement to said blank during the movement of said carriage, said last named means including a rack and a gear carried by said spindle and adapted to roll along said rack during the movement of said carriage, and a plunger carrying said rack thereon and operable to move it into and out of the path of travel of said gear, said rack consisting of a plurality of longitudinal sections, the teeth of one section being normally slightly out of alignment with the corresponding teeth 35 of another section when not engaged by said gear.
5. In a machine of the class described, the combination of a base, a carriage movable thereon, a spindle rotatably carried by said carriage, a blank carried by said spindle and rotatable therewith, a tool disposed in the path of movement of said blank, indexing means for advancing said blank when said carriage has reached a predetermined 45 position on said base, means for imparting a rolling movement to said blank during the movement of said carriage, said last named means including a rack and a gear carried by said spindle and adapted to roll along said rack during the movement of said carriage, and a plunger carrying said rack thereon and operable to move said rack out of the path of travel of said gear just prior to the adjustment of said blank by said indexing means.
6. In a machine of the class described, the combination of a base, a carriage movable thereon, a spindle rotatably carried by said carriage, a blank carried by said spindle and rotatable therewith, a tool disposed in the path of movement of said blank, indexing means for advancing said blank when said carriage has reached a predetermined position on said base, means for imparting a rolling movement to said blank during the movement of said carriage, said last named means including a rack and a gear carried by said spindle and adapted to roll along said rack during the movement of said carriage, and a plunger carrying said rack thereon and operable to move it into and out of the path of travel of said gear, said rack consisting of teeth relatively movable and normally slightly out of alignment when not engaged by said gear.
7. In a machine of the class described, the combination of a base, a carriage movable thereon, a spindle rotatably carried by said carriage, a blank carried by said spindle and rotatable therewith, a tool disposed in the path of movement of said blank, indexing means to advance said blank when said carriage has reached a predetermined position on said base, means for imparting a rolling movement to said blank during the movement of said carriage, said last named means including a rack and a gear carried by said spindle and adapted to roll along said rack during the movement of said carriage, a trip, and a plunger actuated by said trip and carrying said rack thereon to bring it into the path of travel of said gear, means for adjusting said plunger vertically relative to said base and adjustment compensating means intermediate said trip and said plunger for maintaining an operative connection between said plunger and said trip when the former is adjusted vertically.
8. In a gear grinding machine, a work spindle, a gear on the spindle, a rack, means for rolling the gear on the rack to give a rolling movement to the spindle, said rack being movable radially with respect to said gear out of engagement therewith to permit the gear and work spindle to be indexed.
9. In a gear grinding machine, a work spindle, a gear on the spindle, a rack, means for rolling the gear on the rack to give a rolling movement to the spindle, said rack being movable radially with respect to said gear out of engagement therewith to permit the gear and work spindle to be indexed, and indexing means therefor.
10. In a gear grinding machine, a work spindle, a gear on the spindle, a main rack, means for rolling the gear on the rack to give a rolling movement to the spindle, said rack being movable radially with respect to said gear out of engagement therewith to permit the gear and work spindle to be indexed, a supplemental rack for the gear movable longitudinally relatively to the main rack whereby the teeth of said gear may be held in engagement with the teeth of the main rack.
11. In a gear grinding machine, a work spindle, a gear on the spindle, a main rack, means for rolling the gear on the rack to

give a rolling movement to the spindle, said rack being movable radially with respect to said gear out of engagement therewith to permit the gear and work spindle to be indexed, a supplemental rack for the gear 5 movable longitudinally relatively to the main rack, resilient means for moving the supplemental rack to cause the teeth of the gear to be held in engagement with the teeth 10 of the main rack.

12. In a gear grinding machine, a reciprocable carriage, a work spindle rotatably mounted thereon, a gear on the spindle, a rack, means for reciprocating the carriage 15 and for rolling the gear on the rack to give a rolling movement to the spindle, said rack being movable radially with respect to said gear out of engagement therewith to permit the gear and work spindle to be indexed, and 20 automatic means for so moving the rack at a predetermined point in the reciprocatory movement of the carriage.

13. In a gear grinding machine, a reciprocable carriage, a work spindle rotatably mounted thereon, a gear on the spindle, a rack, means for reciprocating the carriage and for rolling the gear on the rack to give a rolling movement to the spindle, said rack being movable radially with respect to said 25 gear out of engagement therewith to permit the gear and work spindle to be indexed, and automatic means for so moving the rack for 30 indexing the gear and spindle and for returning the rack to engaged position with the gear 35 at a predetermined point in the reciprocatory movement of the carriage.

14. In a gear grinding machine, a reciprocable carriage, a work spindle rotatably supported thereon, power actuated means for 40 reciprocating the carriage and giving a rolling movement to the work spindle, means for indexing the work spindle after a predetermined number of reciprocatory movements, automatic means for stopping the reciprocatory movement at the end of a predetermined 45 number of reciprocatory and indexing movements and for simultaneously connecting a wheel dresser to the source of power, and automatic means for disconnecting the 50 machine from the source of power to stop it after a predetermined number of reciprocatory and indexing movements.

15. In a machine of the class described, a work spindle, a gear thereon, a rack, means 55 for rolling the gear on the rack to give a rolling movement to the work spindle, means for withdrawing the rack from the gear by movement in a direction radial with respect to the gear, and for returning the rack into meshed engagement with the gear in indexed relation thereto.

16. In a machine of the class described, a work spindle, a gear thereon, a rack, means 60 for rolling the gear on the rack to give a rolling movement to the work spindle, means for 65

withdrawing the rack from the gear by movement in a direction radial with respect to the gear, means for indexing the gear while the rack is withdrawn and for returning the rack into meshed engagement with the gear in indexed relation thereto. 70

17. In a machine of the class described, a work spindle, a gear thereon, a rack, means for causing relative rolling movement between the gear and rack whereby the spindle 75 is given a rolling movement, means for disengaging the gear and rack by relative movement thereof in a direction radial with respect to the gear and for re-engaging the gear and rack in indexed relation. 80

18. In a gear grinding machine in which the gear tooth faces are ground on the planular face of a rotary grinding wheel by relative movement between the gear and wheel, which movement is that of the gear rolling 85 on a rack, one tooth face of which rack and the face of the wheel are in a common plane, automatic power actuated means for maintaining said planular face approximately in said plane within predetermined limits, 90 which includes means for advancing the planular face axially at the end of a predetermined number of tooth face grinding operations and then moving a dressing element on the planular face in said plane; and means 95 for adjustably positioning said element so as to move in said plane comprising a reference station on the machine and in said plane toward and from which said element may be adjusted. 100

19. In a gear grinding machine in which the gear tooth faces are ground on the planular face of a rotary grinding wheel by relative movement between the gear and wheel, which movement is that of the gear rolling on a rack, one tooth face of which rack and the face of the wheel are in a common plane, automatic power actuated means for maintaining said planular face approximately in said plane within predetermined limits, which includes means for advancing the planular face axially at the end of a predetermined number of tooth face grinding operations and then moving a dressing element on the planular face in said plane; and means for adjustably positioning said element so as to move in said plane comprising a reference station on the machine and in said plane toward and from which said element may be adjusted; said machine having also a clutch device adapted to operate automatically at the end of a predetermined number of grinding operations to disconnect the gear grinding mechanism from the source of power and to simultaneously connect said plane maintaining means thereto. 110 115 120

20. In a machine of the class described, a base, a carriage reciprocable thereon, a work spindle on the carriage adapted to support a gear blank thereon, means for reciprocating the carriage, a tool disposed in the path of 130

movement of the blank on the carriage, means for indexing said blank with respect to the tool at a predetermined position of the carriage, said means including a rack, a pinion meshing therewith, means for moving the rack longitudinally in timed relation to the movement of the carriage, and connections between said pinion and the work spindle.

21. In a machine of the class described, a base, a carriage reciprocable thereon, a work spindle on the carriage adapted to support a gear blank thereon, means for reciprocating the carriage, a tool disposed in the path of movement of the blank on the carriage, means for indexing said blank with respect to the tool at a predetermined position of the carriage, said means including a rack, a pinion meshing therewith, means for moving the rack longitudinally in timed relation to the movement of the carriage, and rotary connections between said pinion and the work spindle.

22. In a machine of the class described, a base, a carriage reciprocable thereon, a work spindle on the carriage adapted to support a gear blank thereon, means for reciprocating

the carriage, a tool disposed in the path of movement of the blank on the carriage, means for indexing said blank with respect to the tool at a predetermined position of the carriage, said means including a rack, a pinion meshing therewith, means for moving the rack longitudinally in timed relation to the movement of the carriage, a ratchet wheel on the spindle, a pawl therefor, and gear connections between the pawl and the pinion.

23. In a gear grinding machine, a main frame, a planular faced rotary grinding wheel, a carriage reciprocable on the frame, means for reciprocating the carriage, a work spindle on the carriage adapted to support a gear blank thereon, a master rack, a master gear on the work spindle adapted to mesh with and roll upon the rack, a rack support on the frame below the rack for supporting it and vertically movable on the frame for adjustably moving the rack upwardly toward and downwardly away from the master gear.

In testimony whereof I hereunto affix my signature this 12th day of August, 1925.

CHARLES H. SCHURR.
